UNITED STATES PATENT OFFICE.

WILLIAM SCOTT, OF JACKSONVILLE, FLORIDA, ASSIGNOR OF ONE-SIXTH TO JOSEPH B. GOLDSMITH AND ONE-SIXTH TO JACOB SHAMSKY, BOTH OF ST. LOUIS, MISSOURI.

COMBINED AUTO JACK AND SAFETY-BRAKE.

1,370,491.

Specification of Letters Patent.

Patented Mar. 1, 1921.

Application filed December 20, 1919. Serial No. 346,403.

To all whom it may concern:

Be it known that I, WILLIAM SCOTT, a citizen of the United States, residing at Jacksonville, in the county of Duval and 5 State of Florida, have invented new and useful Improvements in Combined Auto Jacks and Safety-Brakes, of which the following is a specification.

This invention relates to a combined jack 10 and safety brake for automobiles and the principal object of the invention is to provide a jack for every wheel of the vehicle with means for actuating said jacks by the motor or manually.

Another object of the invention is to provide means whereby each jack may be actuated independently of the other jacks or all together.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is a plan view showing the application of the invention.

Fig. 2 is a detail view showing the jack applied to the front axle.

35 Fig. 3 is a side view of Fig. 2.

Fig. 4 is a view showing the jack applied to the rear axle.

Fig. 5 is a side view of Fig. 4.

40 Fig. 6 is a cross section showing the controlling means for the jack.

Fig. 7 is a plan view of the pedal means shown in Fig. 6.

Fig. 8 is a side view of the actuating lever and its associated parts.

45 Fig. 9 is a front view of said lever.

Fig. 10 is a detail view.

In these views A indicates the frame of the automobile, 1 the rear axle, 2 the front axle and 3 the wheels. In carrying out my 50 invention I secure a pair of jacks 4 on the front axle and a pair of jacks 5 on the rear axle, each jack being located adjacent a wheel.

Each of the front jacks consists of a member 6 formed of two parts and bolted to the

axle. This member is provided with a pair of vertically arranged holes 7 to slidably receive the uprights 8. Cross pieces 9 connect the ends of the uprights together at their upper and lower ends. A spring 10 connects the lower cross piece with the member 6 and tends to hold the jack at its upper and inoperative position and also against a drum 11 which is located on a shaft 12 rotatably supported by the frame A of the vehicle. A cable 13 has one end secured to the drum and its other end secured to the upper cross piece and said cable passes around a pulley 14 carried by the member 6. This cable is so arranged that as the shaft and drum is rotated the cable will be wound upon the drum and the jack lowered against the action of the spring.

The rear jacks 5 are similarly formed excepting the lower cross pieces 9' of these jacks are provided with beveled front ends, as shown in Fig. 5, to permit these pieces to slide along the road surface without digging into said surface. These rear jacks are also provided with a brace 15, each of which is pivoted to the cross pieces 9' and has its upper end slotted as at 16 to engage a bolt 17 on the frame A. These brace pieces will prevent any tendency of the rear jacks to rotate on the rear axle when the jacks are dropped with the car under motion.

Each of the shafts 12 extends to the central part of the frame and each shaft is provided with a crank 18 at its end and a crank 19 intermediate its ends. Each of the cranks 18 is connected with a rack bar 20. These rack bars are slidably supported on the rollers 21 and 21'. The pair of rack bars on one side of the vehicle are arranged above the plane of the pair of rack bars on the other side of the vehicle and the two pairs have their teeth oppositely arranged as shown in Fig. 6. Toothed wheels 22 are secured to the drive shaft 23 and these wheels are located between the upper and lower pairs of rack bars. The rollers 21, which are carried by the supporting brackets 24, will support the lower rack bars in a position with their teeth spaced from said wheels and the springs 25 carried by the brackets 26 will force the rollers 21' upwardly to throw the upper rack bars against rollers 27 carried by the rods 28. In this position the upper rack bars will also be spaced from the toothed wheels. The rods 110

28 are slidably supported in the frame 29 and pass through the floor of the automobile. Their upper ends are provided with the tread parts 30. A pair of slideable rods 31 also pass through the floor and has the tread parts 32 and these rods are connected with the brackets 24 by the levers 33 which are pivoted intermediate their ends to the frame 29, as at 34. It will thus be seen that 10 when one of the rods 28 or 31 is depressed by the foot of the operator pressing on its tread part, one of the rack bars will be brought into engagement with one of the toothed wheels and as said wheels are being 15 rotated by the drive shaft the rack bar will be moved inwardly and thus the shaft 12 connected with said rack bar will be rotated to cause the drum to wind up the cable and thus lower the jack.

20 I provide means for bringing all of the rack bars into engagement with the toothed wheels simultaneously, such means consisting of a cross piece 35 having a tread part 36 arranged over the upper ends of the rods 28 and 31. This cross piece is provided with a vertically disposed part 37 at each end thereof which passes through the floor and a part of the frame 29 in which it is slidably supported. A spring 38 on each of the 30 parts 37 tends to hold the cross piece in its upper position. By pressing on the part 36 with the foot the cross piece 35 will be lowered and thus all the rods 28 and 31 will be lowered to throw all the rack bars in engagement with their toothed wheels and thus all the jacks will be lowered to raise all 35 four of the wheels off the ground.

In order to lower the jacks manually I 40 provide a lever 39 pivoted to the frame of the vehicle and provided with the usual hand operated dog 40, which co-operates with the segment 41. Four arms 42 are pivoted on the pivot pin 43 of the lever and their upper ends are notched as at 44. Each of 45 these notches is adapted to be engaged by a latch 45 carried by the lever 39 so that anyone or all of said arms may be connected with the lever. The lower ends of said arms are connected with the cranks 19 of the 50 shafts 12 by means of the cables 46, the bell cranks 47 and rods 48. The cables, actuating the front shafts pass over pulleys 49.

It will thus be seen that by locking the proper arm 42 to the lever 39 by its latch the 55 desired jack may be actuated or by locking all of said arms to the lever all of the jacks may be actuated. When the jacks are lowered by the motor driven means it is necessary to keep them in lowered position by the 60 hand operated means just described as otherwise the springs 10 would return the jacks to inoperative position.

It will thus be seen that any desired wheel 65 may be raised off the ground either by the motor driven means or manually, or two

three or four of the wheels may be raised if desired.

My invention may also be used as an emergency brake when it is desired to stop the vehicle suddenly to prevent an accident. 70 On such an occasion the two rear jacks are lowered to throw the rear wheels out of contact with the ground. When this is done the cross pieces 9' of the rear jacks will slide a short distance on the road surface but this 75 distance will be so slight that the vehicle will be practically brought to a dead stop.

I may provide a key actuated lock for the dog 40 as shown at 40' to prevent unauthorized use of the automobile. I may also provide an offset shoulder 20* on the rack bars 20 which are adapted to engage a collar 22* 80 on the toothed wheel 22 to throw said rack bars out of engagement with the toothed wheel at the proper time.

85 It is thought from the foregoing description that the advantages and novel features of my invention will be readily apparent.

I desire it to be understood that I may make changes in the construction and in the 90 combination and arrangement of the several parts, provided that such changes fall within the scope of the appended claims.

What I claim is:—

1. In combination with a motor driven 95 vehicle, a pair of jacks connected with each axle adjacent the wheels, means for normally holding said jacks in raised position, means for connecting each jack with the driven shaft of the vehicle and manually operated means for moving any one or all of the said connecting means into and out of operative position.

2. In combination with a motor vehicle, a 105 pair of jacks carried by each axle, means for normally holding said jacks in raised position, means for connecting each jack with the driven shaft of the vehicle, manually operated means for moving any one or all of the said connecting means into and out of 110 operative position and manually operated means for actuating the jack operating means.

3. In combination with a motor vehicle, a 115 pair of jacks connected with each axle, actuating means for lowering each jack, means for connecting said actuating means with the driven shaft of the vehicle, manually operated means forming part of the connecting means and manually operating means 120 for holding the jacks in lowered positions after they are lowered by the before mentioned actuating means, and means for automatically raising the jacks when released from the holding means.

125 4. In combination with a motor driven vehicle, a pair of jacks connected with each axle, means for normally holding said jacks in raised position, actuating means for lowering the jacks, means for connecting said 130

actuating means with the driven shaft of the vehicle, such means including manually operated means, a hand lever and means connecting the hand lever with the actuating means, said connecting means including means for connecting the hand lever with any one or all of the actuating means.

5. In combination with a motor driven vehicle, a pair of jacks connected with each 10 axle, springs for normally holding the jacks in raised position, a pair of shafts located on each side of the vehicle, a drum on each shaft a cable connecting each drum with each jack, a pair of cranks on each shaft, a 15 rack bar connected with one of the cranks on each shaft, toothed wheels secured to the driven shaft of the vehicle, foot operated means for moving any one or all of said rack bars into engagement with the toothed 20 wheels, a hand lever, four arms associated with the hand lever, means for connecting

each arm with the other crank on each shaft and latch means for connecting each of said arms with the lever.

6. In combination with a motor vehicle, a 25 pair of jacks connected with each axle thereof, a drum for each jack, a flexible member connecting each drum with each jack, manually operated means for rotating the drums to lower the jacks, and means for automatically returning the jacks to raised position.

7. In combination with a motor driven vehicle, a pair of jacks connected with each axle thereof, a drum for each jack, a cable connecting the drum with the jack, means 35 for rotating the drums by the driven shaft of the vehicle to lower the jacks, and spring means for automatically returning the jacks to raised position.

In testimony whereof I affix my signature. 40

WILLIAM SCOTT.
